COIN GAUGE

George A. Long, Hartford, Conn., assignor to The
Gray Telephone Pay Station Company, Hart-
ford, Conn., a corporation of Connecticut

Application May 27, 1935, Serial No. 23,723

4 Claims. (Cl. 194—102)

My invention relates to devices employed in connection with coin operated machines, and particularly telephone pay stations, for receiving the coins which are deposited for the use of the machine, and an object of my invention, among others, is to provide a coin gauge that shall be light in construction, pleasing in appearance, and having characteristics enabling it to be rapidly produced.

10 One form of a coin gauge embodying my invention and in the construction and use of which the objects herein set out, as well as others, may be attained is illustrated in the accompanying drawing in which

15 Figure 1 is a view in front elevation of my improved coin gauge.

Figure 2 is an end view of the same.

Figure 3 is a top view.

Figure 4 is a bottom view.

20 Figure 5 is a view in cross section on a plane denoted by the dotted line 5—5 of Fig. 1.

Figure 6 is a similar view on a plane denoted by the dotted line 6—6 of Fig. 1.

Figure 7 is another similar view on a plane de-
25 noted by the dotted line 7—7 of Fig. 1.

Figure 8 is a view in lengthwise section on a plane denoted by the dotted line 8—8 of Fig. 4.

Figure 9 is a similar view on a plane denoted by the dotted line 9—9 of Fig. 4.

30 While my invention is illustrated and described herein in connection with coin gauges used in telephone toll apparatus it will be obvious that it may be readily adapted to coin controlled apparatus of various sorts.

35 Coin gauges, so far as I am aware, have heretofore been made by casting processes and by stamping processes and, in any event, have been composed of a number of pieces. In the practice of my present invention I propose to construct the coin gauge of a single piece of metal and I have arranged a process of casting whereby such coin gauges may be produced in a rapid and efficient manner.

In the accompanying drawing the numeral 10
40 denotes the body of the gauge having a flange 11
at its lower edge provided with ears 12 with holes
therein as a means for securing the device in
place to an instrument in connection with which
it is to be used. Coin openings 13—14—15 are
45 formed through the front wall of the body 10
for the reception of coins, as twenty-five, ten and
five cent pieces respectively. The opening 15
extends from the face of the front wall to a point
quite close to the rear surface of the body, and
50 as shown in Fig. 5 of the drawing. A ledge
55

16 extends from the front wall of the gauge in-
wardly to a point spaced from the rear wall of
the opening 15, thereby creating a coin slot 17
extending from the opening 15 through the bot-
tom of the gauge. This ledge is preferably of
5 arcuate form and provides a portion of a cham-
ber 18 underneath said ledge as well as under-
neath a similar ledge 19 similarly formed and lo-
cated underneath the coin opening 14, and as
shown in Fig. 8 of the drawing. The ledge 19
10 terminates at a distance from the rear wall of
the opening 14 to create a slot 20 extending from
the opening 14 to the bottom of the gauge. Holes
21 and 22 are formed through the rear walls
15 of the openings 14—15 for a purpose to be here-
inafter described.

The coin channel from the opening 15 com-
prises the slot 17 and a passage formed by lips
23 on opposite sides of the passage, and the same
structure is present as to the channel from the 20
opening 14 in which lips 24 are employed, and as
shown in Fig. 4 of the drawing. The shapes
of the ledges 16 and 19 create recesses 25, 26
and 27 in the ceiling of the chamber 18.

The coin slot 28 from the opening 13 is con-
tinuous to the bottom edge of the gauge, that
is, the lips hereinbefore described with respect to
the coin passages from the openings 14—15 are
not present. This channel, however, has a back
wall 29 spaced from the rear wall of the gauge 30
thereby creating an extension 30 of the chamber
18 offset from the main part of the chamber and
communicating therewith by means of the re-
cess 27.

The bottoms of the several coin openings 35
contain numerals designating the denominations of
the coins to be used in such openings, as twenty-
five cents for the opening 13, ten cents for the
opening 14 and five cents for the opening 15,
these numerals being preferably intaglio forma-
tions.

A material feature of my improved coin gauge
just described consists in the body composed of a
single piece of metal which is of minimum thick-
ness and which has a back surface presenting an 45
even area to avoid all projections, humps, or de-
pressions. The interior is chambered to provide
lightness, this chamber extending from end to
end and back of the bottom wall of a shallow coin
opening. This chamber is for the purpose of 50
producing lightness in the structure, and in ex-
tending this feature of chambering the body lips
forming coin guides are provided.

Holes 31 registering each with the other are
formed through the wall 29 and the back of the 55

gauge, registering with the coin openings 13, these holes as well as the holes 21—22 being for the purpose of receiving an instrument, as a lead pencil, for removing a deformed or mutilated 5 coin that may remain in the coin openings and not pass down the coin slots.

I claim:

1. A coin gauge including a body formed from a single piece of metal and comprising a back 10 having an even outer surface with a shallow coin opening and a deeper coin opening in its front face, and coin slots extending from the bottom of said openings to the bottom of the body, said deeper coin opening having a ledge 15 creating an enlarged chamber underneath it, said coin slot being independent of said chamber although opening into it.

2. A coin gauge including a body formed from a single piece of metal and comprising a back 20 having an even outer surface with a shallow coin opening and a deeper coin opening in its front face, said body being chambered underneath the deeper coin opening, said chamber extending continuously from underneath the deeper coin open-

ing to a location behind the bottom of the shallow coin opening, and coin slots extending independently of said chamber from the bottoms of said openings to the bottom edge of the body.

3. A coin gauge including a body formed from 5 a single piece of metal and comprising a back having an even outer surface with a chambered coin opening and a deeper coin opening in its front face, said body being chambered underneath the deeper coin opening, said chamber extending 10 behind the bottom of the shallow coin opening, and lips projecting into said chamber to provide a guide for a coin from the deeper coin opening to the bottom of said body.

4. A coin gauge including a body formed from 15 a single piece of metal having coin openings in its front face, a plurality of said openings having ledges at their bottoms said ledges being of curved form to create a chamber underneath said ledges, and a chamber formed back of one of 20 said openings which is shallower than the other openings, said chambers all communicating with each other.

GEORGE A. LONG.
